UNITED STATES PATENT OFFICE.

ARTHUR TREVOR DAWSON, GEORGE EDWIN WATT, AND ARTHUR LEONARD PERHAM,
OF WESTMINSTER, LONDON, ENGLAND, ASSIGNORS TO VICKERS LIMITED, OF WEST-
MINSTER, LONDON, ENGLAND.

MEANS FOR USE IN THE LAYING OF ORDNANCE.

Application filed October 31, 1919. Serial No. 334,736.

To all whom it may concern:

Be it known that we, ARTHUR TREVOR DAWSON, GEORGE EDWIN WATT, and ARTHUR LEONARD PERHAM, all subjects of the King of Great Britain, residing at Vickers House, Broadway, Westminster, in the county of London, England, have invented certain new and useful Improvements in or Relating to Means for Use in the Laying of Ordnance, of which the following is a specification.

This invention relates to means for use in the laying of ordnance in elevation in accordance with information or indications transmitted from apparatus at a controlling or sighting station situated at a distance from the gun or guns. The chief object of our invention is to eliminate errors in the gun elevation caused by the axis about which the gun is trained not being truly vertical. In the case of a group of guns mounted on turntables supported by rollers from a roller path, for instance, it is rare for the planes of the several roller paths to be parallel and the result is that differences in the gun elevations are caused, the amounts varying at different angles of training or bearing. With a gun on a turntable on a perfectly level roller path, no variation in its angle of elevation will occur at any angle of training of the turntable. But if the whole roller path be tilted, then as the gun is trained towards the raised point its elevation increases and conversely as the gun is trained towards the lowest point, its elevation decreases. The alteration in elevation at any angle of training will vary almost exactly in proportion to the sine of the angle of training as measured from the plane which is normal to the plane of the roller path and passing through the axis about which the roller path has been tilted. If the variations in elevation were plotted as ordinates spaced equally and numbered in accordance with angles of training, the resultant curve would be almost a true sine curve, and the highest point in the curve would indicate the angle of training where the elevation error due to the tilt is greatest, whilst the height of the ordinate at that point would represent according to the scale used the amount of the angle at which the roller path was tilted from the horizontal.

According to the present invention, we

provide means for correcting the errors arising from the above stated causes, which means may comprise a crank adapted to rotate in unison with the turntable and to transmit its motion to the elevation indicating apparatus of the gun, the throw of the said crank being capable of adjustment and also its angular relationship with the turntable so that it will be on its dead centres when the gun is at those angles of training at which the elevation error due to the tilt is a maximum. These adjustments are made after the tilt errors of the turntable have been measured and plotted to ascertain the amount of the tilt and the angles of training at which the consequent elevation error is a maximum. The motion of the pin of the crank is then transmitted by a connecting rod or crosshead to the elevation indicating apparatus. The motion derived from the crank may however be applied by any other means that is appropriate to the particular system of control by which the gun is laid in elevation.

The invention is also applicable to sighting or observing apparatus for correcting errors caused by the tilt of the training axis of the apparatus.

The invention is described above as comprising an adjustable crank as in general a crank is the most convenient device to adopt, but any equivalent mechanism (such as a swash plate) from which a harmonic motion, adjustable in phase relatively to the gun turntable and also adjustable in amount, can be derived, may be used instead of the crank.

To cause the crank or its equivalent to rotate in unison with the turntable of the gun mounting or other apparatus, any form of mechanical gearing may be employed, or the corrector may if desired be set by hand to the angle of training.

Alternatively we may arrange that the corrector is rotated by an electric step-by-step motor or the like receiving current from a transmitter. This transmitter may be geared to the training gear of the gun mounting, or the electric motor may be adapted to work off the electrical circuit appertaining to the system of distant control of the gun training in cases where such a system is in use.

In order that the said invention may be

more clearly understood and readily carried into effect, the same will now be described more fully with reference to the accompanying drawings, in which:—

Figures 1 and 2 are respectively a front elevation and a section taken approximately on the line 2—2 of Figure 1 shewing a form of apparatus constructed in accordance with our invention.

Figures 3 and 4 illustrate apparatus constructed substantially as shewn by Figures 1 and 2 in association with two forms of elevation indicating apparatus, and

Figure 5 is a view shewing a form of apparatus constructed in accordance with our invention for use with the sight at the controlling or sighting station from which the elevation of the gun or guns is controlled.

Referring to Figures 1 and 2, A is a plate which is recessed as shewn by Figure 2 to receive a disc B and which is marked with a circle of graduations A' representing angles of training or bearing and C is a stationary mark or pointer against which the said graduations can be read. The disc B has an arrow mark B' by means of which and the graduations A', the disc can be initially adjusted to the angle of training giving the maximum elevation error; the disc also has a diametrical slot B² for the reception of a sliding block, or crank D having a pin D' connected to a rod E by which correctional movement is given to the part requiring it. This block D is marked with an arrow d and the contiguous part of the disc is marked with graduations representing different angles of the tilt, it being observed that when the arrow d is opposite the zero graduation the axis of the pin D' and that of the disc B are in alignment. The block D is revolved from the training mechanism of the gun turntable, exactly in accordance with the angles of training, by a shaft f carrying a worm F which gears with a worm wheel F' carried by an axial extension or boss A² of the plate A; the block D is clamped to the disc B and the latter to the plate A by a single central bolt G having a T-shaped head which engages in a correspondingly shaped slot formed in the block D. Thus when the disc B has been adjusted to the angle of training or bearing at which the maximum elevation error occurs and the block D has been adjusted to the angle of tilt and these parts clamped as described above, the angular displacement of the block D in unison with the training movements of the turntable will cause the connecting rod E to be displaced in accordance with the amount of correction that is required to be given to the angle of elevation of the gun.

Figure 3 shews how apparatus constructed substantially in accordance with Figures 1 and 2 may be employed in conjunction with a gun elevation indicating instrument simi-

lar to that shewn by Figures 7 and 8 of the drawings of an application for patent filed by us on October 31, 1919, and serially numbered 334,735.

In the construction shewn by Figure 3 the crank D operates through a link E upon a block E' slidably mounted in a curved guide in the fixed part of the instrument, this block being marked with an arrow or zero mark E² opposite which the pointer n is brought in laying the gun. The crank thus serves to vary the position of the said arrow or zero mark. The crank D, the disc B and the guide for the block E' are adjustable by a handwheel r and a worm q, a scale E³ on the fixed part of the instrument shewing the amount of adjustment given.

Figure 4 is a similar view to Figure 3 shewing how the correcting apparatus can be used in conjunction with another form of indicating instrument such as that shown in Figs. 5 and 6 of our said application for patent Serial Number 334,735. The crank D in this case operates through a link E upon a block E' which has an arrow or zero mark E² and is arranged to move in a curved guide in the fixed part of the instrument; the disc B is carried by the fixed part of the instrument. In the lower portion of the instrument is a worm gearing and a handle for operating it to effect an angular movement of the casing carrying the indicator pointers and the motor for operating them in an opening in the frame of the instrument in which this casing is mounted; the casing has at its periphery a series of scale markings as is shown in Fig. 4 for cooperation with the index E² upon the block E'.

Figure 5 illustrates our invention applied to the sight at the controlling or sighting station, which is shown of the same general type as that disclosed in our copending application, Serial No. 403,432, filed August 13, 1920. H is the controlling sight and H' is the handwheel by which elevating movement is imparted to the sight through gearing comprising a worm h, and H' is an elevation transmitting switch operated by the handwheel H'. K is a shaft from which the training movement of the sight is transmitted to the disc B and the block D as described with reference to Figures 1 and 2. The correctional movement given to the connecting rod E by the pin D' of the block D is effected through a lever E^x to shift the worm h axially (a sliding connection being provided between the worm spindle and the part operating it) so that the sight receives in addition to the movement in elevation or depression given it by the handwheel H', a correctional movement in elevation to compensate for the error caused by the training axis of the sight not being truly vertical. Thus in keeping the sight on the target by

operating the handwheel H', the switch H² will be caused to transmit the correct elevation to the receiving instruments at the gun or guns.

6. What we claim and desire to secure by Letters Patent of the United States is:—

1. Apparatus of the character described, comprising the combination of a shaft adapted to be rotated in accordance with 10 training movements of an ordnance device to be laid in elevation, a member driven by the shaft, an element adjustable to various positions radially of said member and adapted to be secured to the member in any adjusted position, a connecting member secured 15 to the element and an indicating member moved by the connecting member to indicate a correction for divergence from the vertical of the axis about which the ordnance device 20 is rotated in train.
2. In ordnance apparatus, an ordnance element adapted to be moved in training and in elevation, a member connected to the element to be rotated in accordance with training 25 movements of the element, a connecting device adapted to be connected to the member at any one of a plurality of positions at different distances from its axis of rotation, and a second member which is connected to and 30 moved by the said connecting device whereby that member is positioned in correspondence with the magnitude of a correction for divergence from the vertical of the axis about which the said element rotates in training.
3. Apparatus for use in laying a gun subject to errors due to the position in train of the gun and the deviation of the position of the gun from a reference line, comprising an instrument in accordance with which the 35 gun is laid, a device movable in unison with the training movements of the gun, means for adjusting the device in accordance with the deviation of the position of the gun from the reference line, means for adjusting the 40 device to agree with the training angle of the gun at which the maximum error occurs and means associated with the device for imparting a correctional movement to the instrument.
4. Apparatus for use in laying a gun subject to errors due to the position in train of the gun and the deviation of the position of the gun from a reference line, comprising an instrument in accordance with which the 45 gun is laid, a rotary variable-throw device, means for angularly moving said device in unison with the training movements of the gun, means for adjusting the throw of the device in accordance with the deviation of the 50 position of the gun from the reference

line, means for adjusting the device angularly to agree with the angle of training of the gun at which the maximum error occurs and means associated with the device for imparting a correctional movement to the instrument. 65

5. Apparatus for use in the laying of ordnance in elevation, comprising a device movable in unison with the training movements of the gun, means for adjusting said device 70 in accordance with the angle by which the training axis of the gun is tilted from the vertical, means for adjusting said device to agree with the angle of training of the gun at which the tilt of the training axis causes the maximum error in elevation to occur and a member which, when said device has been adjusted and is moved as stated, will be given a movement corresponding to the errors in the elevation of the gun at different 75 angles of training, due to the training axis being tilted from the vertical. 80

6. Apparatus for use in the laying of ordnance in elevation, comprising an instrument in accordance with which the gun is elevated, a device movable in unison with the training movements of the gun, means for adjusting said device in accordance with the angle by which the training axis of the gun is tilted from the vertical, means for adjusting said device to agree with the angle of training of the gun at which the tilt of the training axis causes the maximum error in elevation to occur, and means whereby, when said device has been adjusted and is moved as 85 stated, a correctional movement will be imparted to said instrument. 90

7. Apparatus for use in the laying of ordnance in elevation, comprising an instrument in accordance with which the gun is elevated, a rotary variable-throw device, means for angularly moving said device in unison with the training movements of the gun, means for adjusting the throw of said device in accordance with the angle by which the training axis of the gun is tilted from the vertical, means for adjusting said device angularly to agree with the angle of training of the gun at which the tilt of the training axis causes the maximum error in elevation to occur, and means whereby, when said device has been adjusted and is moved as stated, a correctional movement will be 100 imparted to said instrument. 105

In testimony whereof we affix our signatures. 110
